UNITED STATES PATENT OFFICE.

HUGH W. KIMES, OF DAYTON, OHIO, ASSIGNOR TO VAILE & KIMES, A FIRM COMPOSED
OF J. H. VAILE AND HUGH W. KIMES, BOTH OF DAYTON, OHIO.

FLUID-MOTOR.

1,132,188.

Specification of Letters Patent. Patented Mar. 16, 1915.

Application filed July 14, 1913. Serial No. 778,875.

To all whom it may concern:

Be it known that I, HUGH W. KIMES, a citizen of the United States, residing at Dayton, in the county of Montgomery and State of Ohio, have invented certain new and useful Improvements in Fluid-Motors, of which the following is a specification.

My invention relates to hydraulic motors primarily of a reciprocating type wherein a reciprocating valve controls the fluid to and from a power cylinder to reciprocate its piston and reversely in which the piston controls the fluid to reciprocate a valve. The invention herein, however, is more particularly concerned with the means and method of establishing communication between the cylinders rather than in the control of the fluid, or, in the principle of operation of the motor.

20 To more comprehensively disclose the invention it is presented in a preferred embodiment as a duplex hydraulic motor in which the advantages are more readily apparent.

25 It has been customary heretofore to groove or channel the connecting faces of the power and valve cylinder chests and provide an intermediate division plate to separate the grooves from each other, that is, one set was 30 formed on the base of the valve cylinder chest, and the second formed on the top of the power cylinder chest to form the independent passages. In the duplex form of motor, herein referred to, the valve chest 35 and piston chest are made of cast-iron, with the conduits connecting the valve and power cylinders formed of insert units, comprising a tubing of ductile non-corrodible metal, which permits it to be bent into various 40 shapes, its ends provided with terminals preferably in the nature of annular bosses or plugs so that they can be driven or forced into orifices or bores in the cast-iron body of either the valve or power cylinder chest 45 or both to substantially integrally connect the conduits with the body. As illustrated the insert units are applied within a recess formed in the base of the valve chest, possessing advantage in making separable chest 50 sections and conceal the tubing or insert units when the parts are united.

55 Therefore, an object of my invention is to provide a fluid motor of a pressure operated valve type for controlling the movement of the power piston or pistons, with conduit

inserts secured with the body of the motor to establish communication between two or more cylinders for conveying fluid from one to the other for operating the parts to change the stroke of the piston or pistons. 60

A further object of the invention relates to a coupling unit of bendable tubing having plug terminals, each terminal adapted to be driven into an aperture for uniting two members with a fluid conveying conduit. 65

Many advantages result from the use of the coupling in connecting various cylinders of the fluid motor, as, the major portion of the machine not being exposed to the fluid, to cheapen its cost it may be made of cast-iron, with the conduit of a metal not affected by the chemical properties of the fluid, so as not to become choked by corrosion. It reduces coring complications in casting, for 70 passage coring is eliminated. The couplings are quickly, conveniently and efficiently installed, insuring against leakage and bendable to cross one another to shorten their circuit.

Other features of my invention and objects will be in part obvious from the annexed drawings, and in part indicated in connection therewith by the following analysis of this invention.

The invention accordingly consists in the 85 features or combination of parts and arrangements of elements deducible herefrom, all as more completely outlined herein to enable those skilled in the art to fully comprehend the underlying features thereof that 90 they may embody the same by numerous modifications contemplated by this invention, drawings depicting a preferred form have been annexed as a part of this disclosure, and in such drawings like characters 95 of reference denote corresponding parts throughout all the views, of which:

Figure 1 is a central vertical section through the left piston and valve cylinders of a duplex motor. Fig. 2 is a top plan 100 view of the piston chest. Fig. 3 is a bottom plan view of the valve chest. Fig. 4 is a view similar to Fig. 3, in an unfinished state, illustrating a step in the process of manufacture, and will be more fully described in detail hereinafter. Fig. 5 is a section on line 5—5, Fig. 1. Fig. 6 is a section on line 6—6, Fig. 1. Fig. 7 is a section on line 7—7, Fig. 1. Fig. 8 is a central vertical section on line 8—8, Fig. 7. Fig. 9 is a sec- 110

tion similar to Fig. 7, showing the valves in a reverse or alternate position. Fig. 10 is a central detail section through one of the conduit inserts as a unit. Fig. 11 is a diagrammatic view of the various cylinders and their pistons and the conduits and passages connecting the same for clearly observing the cross principle of two of the valve controlling conduits.

10 The motor comprises a piston chest 1, and a valve chest 2, detachably secured together by bolts or screws. The motor being of duplex type, each chest provides two cylinders adjacent each other. As the piston chest is made of cast-iron, its cylinder bores are lined with cylindrical inserts 3 which respectively form a right power cylinder 4 and a left power cylinder 5. The inserts of each cylinder are of two-part form or intermediately divided or apertured to connect each cylinder with a common exhaust chamber formed intermediately in the piston chest, see Figs. 1 and 2, to be more fully hereinafter described.

25 As both right and left power cylinders and their parts are the duplicates of each other, a detailed description of one will be sufficient. Each power cylinder is provided with a rear removable cylinder head 5', and a front removable cylinder head 6, the head 6 of each cylinder has a stuffing-box 7, through which a piston rod 8 passes and connects to a piston within its cylinder. Each piston comprises a spool 8 concentrically bored to receive the piston rod, with its flanges 9, 10, each respectively providing abutments for the cup packings 12, 12. The cup packings and piston parts are secured together by the flange nuts 13, 13, secured 30 to the piston rod at opposite ends of the piston. The spool form of piston and its cylinder form an intermediate exhaust chamber 11, transferable with the movement of the piston to bring the chamber alternately into communication with different passages. The intermediate chamber 11 is constantly in communication with the exhaust chamber 14, which is common to all cylinders, formed within the motor chests.

45 50 The valve chest 2 has a valve cylinder provided above each power cylinder, respectively designated as a right valve cylinder 15 and a left valve cylinder 16. These are also formed by cylindrical inserts in the bores of the valve chest, and each cylinder has a removable front head 17 and rear head 17'.

55 60 As a duplex motor provides duplicate sets of devices as to construction, operating alternately in succession, in which the fluid from one may control the operation of an element of an opposite set, therefore, in the description herein certain elements or combinations may be defined by their location, 65 without reiterating the specific details of

each. To this end, power cylinder 4 has been designated as a right power cylinder and valve cylinder 15 directly above the same, as the right valve cylinder, and thus all elements or combinations thereof when referred to as right, are embraced within such side of the motor. Similar reference is had as to the left power cylinder 5 and left cylinder 16 and their contained elements. Likewise as to forward and rear locations, the forward portion of the motor being that containing cylinder head 6 though which the piston rod moves, and the rear containing the cylinder head 5'. 70 75

The valve cylinders are each provided 80 with a piston valve, both of duplicate construction, each comprising a valve stem 18, intermediately provided with the spaced flanges 19, 20, supporting respectively the cup packings 21, 22, to form an intermediate 85 exhaust chamber 23, movable with the valve. Upon the forward end of the stem 18, adjacent the flange 20, a spool 24 is detachably secured, one end of the spool engaging the packing 22 and its opposite end supports a cup packing 25, and both secured upon the valve stem by a flange nut 26. The spool with the packing and cylinder provides a fluid supply chamber 27 movable 90 with the valve. The rear end of the valve stem 18 is provided with similar parts, namely, a spool 24', having one end engaging against the packing 21, its opposite end engaging a cup packing 28, and the parts secured upon the stem by a flange nut 29. The 95 spool with its packings and cylinder form a rear water supply chamber 29' movable with the valve. The supply chambers 27 and 29' produce a normally balanced valve, with its fluid supply under equal pressure 100 in each chamber and by alternately admitting a pressure against the ends of the valve, it is reciprocated in appropriate direction. A chamber 30 is provided between the forward end of the valve and the front cylinder head 17, designated as a front valve 105 pressure chamber, with a similar chamber between the opposite end of the valve and rear cylinder head 17' as a rear valve pressure chamber 31, each valve cylinder has a plural series of apertures formed around the cylinder serving as ports, some of which are controlled by the valves. 110 115

32 represents a water supply chamber cored within the valve chest, extended so as to communicate, through the perforations 33 of the right and left valve cylinders in common with the forward valve supply chambers 27 and through perforations 34 of both cylinders, with the rear valve supply chambers 29'. The supply chamber 32 has an inlet port 35 in the projection 36 cast integral with the valve chest. Each valve cylinder is provided with a second series of perforations 37, 38, for establishing communi- 120 125 130

cation respectively between the forward valve chamber 27 and the forward portion of its power cylinder, through a conduit 39 formed in the valve and piston chests; the 5 perforations 38, establishing communication between a valve cylinder and the rear end of its power cylinder beneath, through a conduit 40, cored within the valve and piston chests.

10 41 represents an intermediate series of perforations in each valve cylinder to connect with the exhaust chamber 14, see Fig. 5. Thus, as shown in Fig. 1, the position of the valve at one end of its stroke will open 15 the forward valve supply chamber 27 into communication with the forward end of its power cylinder through passage 39 to force the piston rearward or to the left. In such position the valve ports 38, 41, communicate 20 through chamber 23 to open the exhaust side of the power cylinder for exhausting the fluid through passage 40, port 38, chamber 23, port 41, into the exhaust chamber 14, and discharging from the motor through 25 the outlet 42. When the valve is in the reverse position, as shown in Fig. 8, a reverse operation of the parts takes place, in which the active fluid passes through conduit 40 and a discharge through the conduit 39. 30 Therefore, each valve controls the supply and exhaust to the forward and rearward ends of its respective power cylinder.

Valve control.—As heretofore stated, the power pistons control the fluid supply and 35 exhaust to respective valve cylinders for shifting the valves to reverse the movement of the pistons. To accomplish this result conduits or passages connecting the valve and power cylinders are provided, and it is 40 the construction of these conduits which forms the broad aspect of this invention. To gain a clearer conception of the invention, it may be best to begin with the function and location of the conduits or passages, 45 and for this purpose, examination is directed to Fig. 11. This figure, diagrammatically, shows all the conduits and passages connecting the various valve and power cylinders, with their forward ends 50 directed toward the right side of the sheet. A conduit 43 connects the forward portion of the power cylinder 4 with the forward portion of the valve cylinder 16, so that when the piston in cylinder 4 moves rearwardly sufficient to uncover the port to said conduit 43 and admit fluid under pressure therethrough, it will force the valve 16 rearwardly, changing the direction of the supply to the power cylinder 5, for moving the piston 55 rearwardly or to the left from that shown in the drawings. A second conduit 44 connects with the rearward portion of the power cylinder 4 and the rear end of valve cylinder 16. This conduit, as illustrated, is 60 open to the intermediate exhaust chamber of

the piston in cylinder 4, relieving the valve in cylinder 16 of any pressure at such rear end and thereby unbalancing the valve when the pressure is admitted into the forward end of said cylinder. A third conduit 45 70 connects the rear portion of the left power cylinder 5 with the forward portion of the right valve cylinder 15, with the piston in cylinder 5 controlling the supply and exhaust in substantially the same manner, as 75 described, for the piston in cylinder 4. 46 represents a fourth conduit connecting the forward portion of the left power cylinder 5 with the rear portion of the right valve cylinder 15. It will be seen that conduits 80 45, 46, cross each other, and were very difficult to provide, in motors of this class, as heretofore constructed. These passages are of small area, making them very difficult and expensive to core, and if cored, easily 85 clogged from corrosion if the body is made of cast-iron and rendering the motor impractical for the use for which it is primarily intended. That of operating the motor by water pressure from city mains, 90 distributing hard or well water, for operating a pump to distribute soft water taken from cistern for general use in a home or building.

My improvement is to construct the body 95 portions of the motor from cast-iron, with the valve controlling conduits of a ductile non-corrodible material. These conduits are termed insert units, and comprise a bendable tubular element having terminals at each 100 end capable of being driven or forced into apertures in the valve body and thereby substantially form an integral part of the body.

Insert units.—The insert units comprise the conduits or passages 43, 44, 45 and 46 105 for conveying water between the respective valve and power cylinders for controlling the operation of the valves. Their construction within the motor are principally illustrated in Fig. 3 of the drawings, while 110 Fig. 10 illustrates a section of one of the units. These insert units are all similarly constructed and differ only in their particular bent form to reach from one valve cylinder to a respective power cylinder and 115 in describing the same in detail, reference will only be made to one of them. Each unit comprises a tubing element 47, (see Fig. 10), preferably of copper so as to permit the same to be conveniently bent. Each 120 end of the tubing has a terminal element 48, 49 rigidly secured thereto and the joint is fused together to form the two elements substantially integral with each other, and for all purposes may be regarded as integral 125 elements within the scope of this invention. The two-part form of construction being merely for convenience of construction. The union, however, may be constructed in any well known manner. These insert units 130

are embedded within a recess 50, formed in the base or parting surface of the valve chest so as to completely house the units when the chests are put together and separable with the valve chest so as to insure a more permanent connection of the ends or terminals of the units when utilized as couplings between separable members. The terminals 48, 49, are each of circular form and 10 coated with a fusible metal. The fusible metal coating provides a thin film over the terminals which accommodates for any slight variation in size between the relative diameters of the apertures and terminals. The 15 terminals are made from a rod as received from a rolling mill, and for commercial purposes is very accurate in size, although sometimes varying a few thousandths of an inch, and, therefore, the coating insures a proper 20 drive fit between the parts without gaging or special milling of the terminals. The fusible metal also adapts itself to fill the cavities in the walls of the terminal receiving apertures, and acts as a lubricant to aid 25 in driving the terminal into an aperture, as well as a seal to make a water-tight joint. As the coating is applied by dipping, it forms a fillet around the exterior of the tube at its terminal juncture, which securely calks 30 the tubing within the slot cut between the recess 50 and terminal apertures.

It will be observed in the particular usage of the units herein illustrated that the terminals 48, 49 occupy a transverse position 35 relative to the tubing and each provided with an aperture 51 in relative opposing ends of their respective terminals to establish opposing right angular leads for conduit continuity so as to respectively lead to 40 the valve and power cylinders connected together in superposed planes. The aperture of terminal 48 is directed upwardly so as to bring it in communication with the upper valve cylinder while the aperture of the terminal 49 is directed downwardly so as to bring it in communication with a lower power cylinder. It will be observed principally from Figs. 8 and 10, that the terminal 48 at its apertured end has a nipple projected therefrom for a reduction in the 50 diameter of the bore at its entrance into the valve cylinder.

As illustrated in Fig. 3, insert unit 43 is in the nature of a right angle bend having 55 one terminal connecting with the left valve cylinder, while its opposite terminal is adapted to communicate with the right power cylinder. The insert unit 44 is bent similar to insert unit 43, connecting the same 60 valve and power cylinders at the rear end thereof. Insert units 45 and 46 may be termed the cross units which function as heretofore clearly described. By this construction it will be seen that the heretofore 65 complicated methods of constructing such

cross passages is overcome and easily made within the base of the valve chest, dispensing with difficult coring or intermediate plate. Each passage is absolutely independent of the other and is not disturbed when separating the cylinder chests. 70

In the process of manufacture, the valve chest is cast with the recess 50, after which it is drilled so as to form the terminal apertures 53, shown in dotted lines, Fig. 4. 75 These apertures are drilled slightly beyond the marginal line of the recess so as to substantially receive the entire area of the terminals, with a slot cut between the apertures, and the recess to receive and embed 80 the conduit or tubular element of the unit. It is obvious, however, that one of the terminals of the insert units could be connected with the power cylinder which would possibly interfere with the separable feature of 85 the chests, but is contemplated within a broad aspect of this invention. With the units connected to the valve chest it is necessary to provide a conduit insert within the upper portion of the power cylinder in 90 order that the entire length of the passage may be formed of a non-corrodible material, and this I accomplish, as is illustrated in Figs. 1, 6 and 8 by boring the cylinder chest from its upper parting surface to the cylinder. 95 A tubing 54 is driven into such orifice so as to connect the terminal 49 of the insert unit with the power cylinder. This is positioned in registry with the aperture of the terminal and both being of a comparatively 100 soft material form a friction seal when the parts are united.

Having described my invention, I claim:

1. The combination of two chambered members with a bendable conduit unit having terminal plugs apertured for passage continuity, each of said plugs adapted to be driven into an aperture to join said members. 105
2. A coupling unit comprising a bendable tubing element with plug terminals, each terminal apertured for passage continuity through said terminals. 110
3. A coupling unit comprising a bendable tubing element with plug terminals, apertured transversely for passage continuity through said terminals. 115
4. A coupling unit comprising a bendable tubular element having transversely apertured plug terminals, the said apertures entering relative opposing ends of the respective terminals to establish opposing right angular leads for passage continuity through said terminals. 120
5. A fluid motor of the nature disclosed 125 combining a power cylinder, a valve cylinder separably connected with said power cylinder having its parting surface recessed and apertured, and insert conduit units to provide passages for connecting said cyl- 130

- inders, each unit comprising a bendable tubing element having terminals apertured for passage continuity, and each terminal inserted within said valve cylinder apertures 5 with the tubing element embedded within the recess of said cylinder when the cylinders are united to completely house the same.
6. A fluid motor of the nature disclosed 10 combining a power cylinder, a valve cylinder connected to said power cylinder and an insert conduit unit comprising a bendable tubing element having drive terminals apertured transversely for passage continuity, and embedded between said cylinders to establish communication between the cylinders.
7. A fluid motor having duplex power cylinders, duplex valve cylinders, and insert 15 units, each comprising a bendable tubular element having transversely apertured terminals, the said apertures entering relative opposing ends of the respective terminals to establish opposing right angular leads for passage continuity, and connected with one valve cylinder for establishing a passage between one valve cylinder and an opposite power cylinder.
8. A fluid motor of the nature disclosed 20 combining two separable cylinder members and conduit for connecting said cylinders, comprising an insert unit formed of a bendable tubing element having plug terminals apertured for passage continuity, said terminals frictionally inserted within apertures formed in one of said members.
9. A fluid motor of the nature disclosed 25 combining a power piston cylinder, a valve cylinder separably connected to said power piston cylinder, means for connecting said cylinders comprising a bendable tubular element having transverse plug terminals adapted to be secured within apertures formed in one of said cylinders, the relative opposing ends of the respective plug terminals apertured to establish opposing right angular leads for passage continuity, one communicating with the interior of the valve cylinder and the second with the interior of the power cylinder.
10. In a duplex fluid motor, a unit of right and left power cylinders, a unit of left and right valve cylinders, said power and valve cylinders separably connected with the parting surface of said valve cylinders intermediately recessed, a piston in each of said power cylinders each having an intermediate exhaust chamber, a valve in each of said valve cylinders each having three chambers, front and rear supply and intermediate exhaust, an intermediate exhaust passage common to all cylinders and exhaust chambers, a passage for each valve cylinder to the front of its respective power cylinder, a second 30 passage to the rear thereof, conduit inserts within the recess of said valve cylinders, each comprising a bendable tubing with apertured plug terminals, the terminals secured within apertures in said valve cylinders to provide passages between the front 70 and rear of one power cylinder, and the front and rear respectively of the opposite valve cylinder, a second set of conduit inserts within the recess of said valve cylinders comprising a bendable tubing with apertured terminals, the terminals secured within apertures in said valve cylinders to provide passages connecting the front and rear of the second power cylinder with its opposite valve cylinder from the front of one to 75 the rear of the other, whereby the passages serve as supply and exhaust passages in relative alternate valve and piston reciprocations.
11. In a fluid motor, duplex power and valve cylinders with the valve cylinders separable from the power cylinders and the parting surface of the valve cylinders intermediately recessed, a piston reciprocating in each power cylinder, each having an intermediate exhaust chamber, a valve reciprocating in each valve cylinder, said valves each having duplex supply chambers and an intermediate exhaust chamber and exhaust outlet connecting valve and power cylinders, 80 independent passages connecting each valve cylinder intermediately with the forward and rear ends of a respective power cylinder, independent passages connecting the forward and rear ends of one valve cylinder 85 respectively with the forward and rear ends of the opposite power cylinder, each passage comprising an insert conduit unit mounted within the recess of said valve cylinders, each having apertured plug terminals secured within 90 apertures in said valve cylinders, with the aperture of one terminal in registry with an aperture leading to a respective power cylinder, independent passages connecting the forward and rear ends of one valve cylinder 95 respectively with the forward and rear ends of the opposite power cylinder, each passage comprising an insert conduit unit mounted within the recess of said valve cylinders, each having apertured plug terminals secured within 100 apertures in said valve cylinders, with the aperture of one terminal in registry with an aperture leading to a respective power cylinder, independent passages connecting the forward and rear ends of one valve cylinder 105 respectively with the forward and rear ends of the opposite power cylinder, each passage comprising an insert conduit unit mounted within the recess of said valve cylinders, each having apertured plug terminals secured within 110 apertures in said valve cylinders, with the aperture of one terminal in registry with an aperture leading to a respective power cylinder, independent passages connecting the forward and rear ends of one valve cylinder 115 respectively with the forward and rear ends of the opposite power cylinder, each passage comprising an insert conduit unit mounted within the recess of said valve cylinders, each having apertured plug terminals, the terminals secured within apertures in said valve cylinders, the aperture of one terminal in registry with a respective aperture of a respective power cylinder whereby the passages serve as combined supply and exhaust in respective alternate valve and piston reciprocations.
12. A coupling unit comprising a bendable tubing element having one end headed to provide a drive terminal with the tube 125 passage continuous through said terminal.
13. A coupling unit comprising a tubular member having an end provided with a drive terminal for securing unit in place and passage continuity.

14. A coupling unit comprising a tubular member with fusible-metal-coated drive terminals.

15. A coupling unit comprising a member having a fusible-metal-coated plug for securing unit in place.

In testimony whereof, I have hereunto set my hand.

HUGH W. KIMES.
